UNITED STATES PATENT OFFICE.

JOSEPH B. DE LÉRY, OF NEW YORK, N. Y.

INCANDESCENT BURNER.

SPECIFICATION forming part of Letters Patent No. 591,652, dated October 12, 1897.

Application filed March 2, 1897. Serial No. 625,704. (No model.)

To all whom it may concern:

Be it known that I, JOSEPH B. DE LÉRY, a citizen of the United States, residing at New York, in the county of New York and State of New York, have invented certain new and useful Improvements in Incandescent Burners, of which the following is a full, clear, and exact description.

This invention relates to gas-lighting by incandescence; and it consists of certain improvements in burners and the manner of grouping the same, whereby (a) much of the loss heretofore experienced in the destruction of the incandescing mantles is avoided; (b) the renewal of mantles may be accomplished with facility; (c) any member of a group of burners to which the gas-supply is controlled by a single valve may be operated while the remainder are out of operation; (d) equal gas-pressure to each burner of a group is insured, and (e) it is possible to group a certain number of burners into the smallest and most compact space. The construction whereby these objects are accomplished will now be described with reference to the accompanying drawings, in which—

Figure 1 is a side elevation of my improved burner and its mounting. Fig. 2 is a plan of the parts below line αx of Fig. 1. Fig. 3 is a vertical section, on an enlarged scale, of one of the burners without the mantle. Fig. 4 is a perspective view, on an enlarged scale, of the mantle and holder; and Fig. 5 is a view of one of the stoppers.

The general construction of the burner comprises a gas reservoir or box substantially in the shape of a drum, into the upper side of which are tapped a series of burner-tubes individually provided with air-inlets and each carrying an incandescent mantle. Aside from this general construction the invention also comprises certain details of construction relating to the burners.

Referring to the drawings by letter, a represents a cylindrical reservoir or drum directly connected with a gas-pipe a' and into which gas is admitted or cut off at pleasure by a valve a^2 . The upper side of the gas-drum is a disk, around the edge of which is arranged a series of burner-tubes b . These communicate with the interior of the drum by means of nipples c , which also serve as supports for

the tubes. For this purpose the nipples consist of a thick disk c' , having axial projections c^2 from each side. One of these projections screws into a tapped hole in the top of the gas-drum, bringing the disk c' squarely against the wall of the drum. The upper projection is threaded externally for a purpose which will hereinafter appear. A gas-passage c^3 extends through the nipple, and this is made very small, so as to increase the force of the gas flowing through it. The diameter of the disk c' is such that the lower end of tube b will fit tightly over it, it being merely forced into place. This lower end of the tube is provided with lateral openings b' for the ingress of air. At the upper end of the tube an enlarged chamber b^2 is formed, in which is located a deflecting device b^3 in the form of a propeller, which, however, does not rotate on the spindle b^4 , to which it is attached. Above this propeller and across the top of the tube is a screen of wire network b^5 . This deflector b^3 serves to thoroughly mix together the gas flowing through the nipple and the air coming through the lateral openings before they pass out of the burner. Around the top of the burner is placed a thimble b^6 , having an inwardly-turned upper edge the function of which is to hold the wire screen in place. This fits into the burner-tube friction-tight.

e is the incandescent mantle or hood, the means for mounting which upon the burner is a feature of my invention. This consists of a collar f , adapted to pass loosely over the top of the burner outside of the thimble and having an inwardly-turned flange or edge f' , adapted to rest upon the edge of the opening in the burner to support the collar. On one side the collar is provided with a handle f^2 and on the other side with a perforated lug f^3 and binding-screw f^4 . Through the lug a wire f^5 passes and is held in place by the screw. This wire supports the mantle from its upper end, the mantle at its lower end surrounding the opening in the top of the burner-tube. The collar f is merely suspended by its upper edge upon the top of the burner-tube, so that to remove it it is only necessary to lift it off.

I am aware of the existence of a gas-burner wherein a gas drum or reservoir having a series of burners tapped into the same have

been used, but in such instance the air is also admitted into the reservoir with the gas, which I claim not to be as good a feature as the construction described by me, wherein 5 the air is separately admitted to the individual burners outside of the drum. In my way the quantity of air admitted to each burner can be adjusted, whereas by the other way the proportion of air and gas flowing to the 10 several burners is a variable quantity due to the unequal mixing of the gas and air in the drum. Furthermore, it is not desirable to mix a large body of air and gas together. Aside from the matter of mixing the gas and 15 air together the drum to which the supply of gas is controlled by a single valve and to which the burners are directly connected gives an advantage over a construction where- 20 in a cluster of lights is supplied by a series of radial pipes from a common center, as in such latter construction the gas-pressure to the different burners often varies by reason of the clogging of the passages by the deposits from the gas, which is always unequal, 25 and because the pressure to the individual burners cannot be kept so uniform as when a large body of gas in a reservoir is used.

One of the important advantages of my invention is the ease with which broken mantles 30 may be removed and replaced, and the fact that such operation may be accomplished without interfering in the slightest degree with the other mantles of the group. This burner is primarily designed to replace the 35 ordinary average-sized incandescent burner, and the group of small burners here shown will not occupy any more space than the single large burner now in commercial use. Each of my burners is comparatively small, 40 the mantle being only about one and one-half inches long, while the diameter of the drum is about the same dimension. It follows from this that with incandescent ma- 45 terial of the same texture and strength my mantles will resist much greater disturbing forces than the other on account of its lesser area. If, however, the mantle does break, it entails a very small loss, as only a fraction of the entire light-giving elements is destroyed.

Any injured mantle may be removed by sim- 50 ply lifting off the collar *f* supporting it. Another collar, which will always be at hand, having previously had a new mantle attached to it, is then inserted in place by merely dropping the collar over the top of the burner. 55 If a mantle is broken and another is not at hand with which to replace it, or it is only desired to burn some of the mantles, while others are out of use, this may be accom- 60 plished by removing the burner-tube *b* from the nipple and screwing the cap (shown in Fig. 5) onto the outward projection of the nipple, thus stopping the flow of gas to that particular burner and leaving all of the active burners still under the control of the 65 valve *a*².

The deflecting-plate at the outlet of the burner is a good feature of my invention, as it constitutes an effective mixing device for the air and gas just before it enters the man- 70 tle. The fixed blades of the deflector impart a twist to the air and creates currents which thoroughly mix them.

Having thus described my invention, I claim—

1. An incandescent gas-burner consisting of a drum or reservoir to which the gas is admitted, in combination with a plurality of burners attached directly thereto, an incandescent mantle or element mounted upon each 80 burner and means for admitting air to each of the gas-passages between the drum and the incandescent material, whereby uniform pressure and a proper proportion and mixture of air to each burner are insured, substantially 85 as described.

2. In an incandescent burner, the combination of a gas-chamber, a nipple screwed into the same and a burner-tube supported by the nipple and provided with an air-supply pas- 90 sage, said nipple also provided with a gas- passage.

In testimony whereof I subscribe my signature in presence of two witnesses.

JOSEPH B. DE LÉRY.
